CLAIM

The ornamental design for a handle for a toothbrush, as shown and described.

DESCRIPTION

FIG. 1 is a perspective view of a handle for a toothbrush from above, showing our new design;

FIG. 2 is a front view of the appliance thereof;

FIG. 3 is a right side view of the appliance thereof;

FIG. 4 is a back side view of the appliance thereof;

FIG. 5 is a left side view of the appliance thereof;

FIG. 6 is a top plan view of the appliance thereof; and,

FIG. 7 is a bottom plan view of the appliance thereof.

The broken lines shown on the top, bottom, and back of the handle as well as the broken lines shown behind the transparent surface on the front of the handle are included for the purpose of showing portions of the article or environmental structure that form no part of the claimed design.
